CLAIM

The ornamental design for an automated guided vehicle, as shown and described.

DESCRIPTION

This application is also related to U.S. patent application Ser. No. 14/966,978, filed on Dec. 11, 2015; U.S. patent application Ser. No. 14/997,902, filed on Jan. 18, 2016; U.S. patent application Ser. No. 14/997,925, filed on Jan. 18, 2016; U.S. patent application Ser. No. 14/997,920, filed on Jan. 18, 2016; and U.S. patent application Ser. No. 14/997,892, filed on Jan. 18, 2016, the disclosures of which are incorporated herein by reference in their entireties.

FIG. 1 is a front right perspective view of an automated guided vehicle in accordance with one form of the present invention;

FIG. 2 is a front left perspective view of the automated guided vehicle of FIG. 1;

FIG. 3 is a rear left perspective view of the automated guided vehicle of FIG. 1;

FIG. 4 is a top plan view of the automated guided vehicle of FIG. 1;

FIG. 5 is a right side elevation view of the automated guided vehicle of FIG. 1;

FIG. 6 is a front elevation view of the automated guided vehicle of FIG. 1;

FIG. 7 is a rear elevation view of the automated guided vehicle of FIG. 1; and,

FIG. 8 is a left side elevation view of the automated guided vehicle of FIG. 1.

The broken lines in the drawings depict portions of the automated guided vehicle which form no part of the claimed design.

1 Claim, 8 Drawing Sheets
